UNITED STATES PATENT OFFICE.

JOHN C. MALONE, OF BEAVER FALLS, PENNSYLVANIA.

STRAIGHTENING MACHINE.

Application filed August 6, 1924. Serial No. 730,404.

The present invention relates broadly to the art of straightening lengths of material, and more particularly to a machine for the purpose of straightening wire.

At the present time it is customary to straighten wire by the use of a rotating carrier, often in the form of a cylinder, carrying a plurality of rotary dies. Ordinarily, these rotating carriers are provided with at least one pair of adjustable dies adapted to exert varying tension on the wire being straightened. Such straighteners are usually operated by passing the wire through the carriers, then stopping rotation thereof, and adjusting the dies in order to apply the desired tension. This operation is repeated each time a new bundle or coil of wire is to be straightened, thereby requiring a considerable and unnecessary waste of time with a corresponding increased hazard of operation.

In an effort to overcome the defects of straighteners of this character, it has heretofore been proposed to provide an elongated wedge-shaped or tapered operating fork extending axially into the carrier for adjusting one of the dies while the machine is in operation. Such an operating fork has not only required a special form of straightener on which it is adapted to be used, but has been resilient to such an extent that the applied tension varies with the hardness of the wire being straightened. With such constructions, the dies have not been so mounted as to prevent their turning out of alignment in the event no wire was in position within the machine. This has necessitated the taking apart of the cylinder, usually each time a new length of wire was started through the straightener, in order to properly align the dies for its reception. This same taking apart operation has also been required each time the dies had to be changed or polished to remove scratches.

One of the objects of the present invention is to provide an attachment adapted to be applied to any wire straightener having a plurality of rotary dies, and adapted to maintain the dies in predetermined alignment either with or without wire within the straightener, and adapted to be operated to exert a predetermined and uniform tension on the wire irrespective of the physical characteristics thereof. It is also designed to permit easy removal of the dies for chang-

ing or repolishing, while permitting the tension to be applied or relieved without stopping rotation of the straightener, thereby increasing the production and efficiency thereof and at the same time lessening the hazard of operation.

In the accompanying drawings there is shown, for purposes of illustration only, a preferred embodiment of the present invention, it being understood that the drawings do not define the limits of the invention as changes in the type of the straightener and in the construction and operation of the die adjusting means may be made without departing from the spirit of the invention or scope of my broader claims.

In the drawings:

Figure 1 is a side elevation of one form of straightener embodying the present invention,

Fig. 2 is a vertical sectional view on an enlarged scale, on the line II—II of Fig. 1, looking in the direction of the arrow,

Fig. 3 is a longitudinal sectional view, partly in elevation, along the line III—III of Fig. 2,

Fig. 4 is a perspective view of the adjusting sleeve, and

Fig. 5 is a side elevation of the thrust block.

In wire straighteners of the rotating cylinder type, the adjustable dies are usually of such construction that they are adjusted by the use of a screw, which is obviously adjustable only when the straightener is stationary. In accordance with the present invention the use of such an adjusting screw is entirely eliminated and there is provided a rigid operating mechanism operable at will and effective for exerting a uniform tension on the wire passing through the straightener.

In carrying out the present invention there may be provided a straightener 2 comprising a shaft of any desired construction, having supporting trunnions 3 mounted for rotation in suitable bearings 4 in a frame 5 and provided with a pulley 6 adapted to receive a belt for rotating the same.

The straightener as thus described may be of any usual construction. At some point intermediate the ends thereof there is provided a die guiding passage 7 angular in cross-section, the passage being preferably substantially square. In the construction shown, the die guiding passage 7 is located

in the intermediate portion of the straightener, there being two dies 7^a on each side of the passage 7, as clearly shown in dotted lines in Fig. 1. Mounted within this die guide is a die supporting block 8 carrying a fixed die 9 having a wire groove 10 semi-circular in form and adapted to embrace substantially half of the wire being straightened. Above the die block 9 is an adjustable die block 11 having a corresponding wire receiving groove 12 therein. This second die block is adapted to be adjusted radially in order to release the wire or apply a predetermined tension thereto. For effecting such adjustment there is provided a thrust block 13 carrying an anti-friction roller 14 projecting beyond the end of the thrust block, as clearly illustrated in Fig. 2 and 5. It will be apparent that by reason of this construction, in order to effect adjustment of the die block 11 it is only necessary to move the thrust block 13 inwardly to the required extent.

For effecting movement of the die block 11 at any time during the operation of the straightener, there is provided a sleeve 15 movable axially of the die carrier and preferably continuously surrounding the same. This sleeve has an actuating groove 16 extending longitudinally thereof and of substantially constant width but gradually decreasing depth toward one end. In order to permit threading of a length of wire through the die carried between the die blocks 9 and 11 the sleeve will occupy substantially the position indicated in full lines in Fig. 3. After the wire has been threaded between the dies, the desired tension may be applied thereto by moving the sleeve 15 to the right, as viewed in Fig. 3, from its full line to its dotted line position, thereby moving the thrust block 13 inwardly to move the die block 11 into cooperative engagement with the die block 9. It will be apparent that the amount of movement imparted to the sleeve 15 will control the position of the die block 11 and that due to the fact that the sleeve exerts a direct thrust on this die block the position thereof, for a given position of the sleeve, will always be the same irrespective of any changes in the physical characteristics of different lengths of wire being operated upon. This constitutes an important feature of the present invention as it eliminates yielding of the die blocks as is permitted where a more or less elongated operating fork is utilized.

For effecting movement of the sleeve as may be required, it is preferably provided with a peripheral groove 17 adapted to receive shoes 18 carried by pins 19 extending inwardly from the arms of a shifter yoke 20. This shifter yoke may be provided with trunnions journaled in suitable bearings 21 carried by standards 22 projecting upwardly

from the frame 5 of the straightener. One of the trunnions may carry an enlargement 23 adapted to have an operating lever 24 secured thereto for effecting rocking of the shifter yoke. This lever may be shifted by hand, as will be apparent from an inspection of Fig. 1, or may be shifted by a foot lever 25 operatively connected to the hand lever by a link 26. By this construction the sleeve 15 may be quickly and at will moved axially of the carrier to any desired position to thereby apply the desired tension to the wire being straightened.

The angular cross-section of the die guide 7 prevents the dies from turning out of alignment even though no wire is present within the straightener. This makes it impossible for the dies to turn out of alignment and insures the proper positioning of the grooves 10 and 12 at all times. When it is desired to change the dies, or repolish the same to remove scratches or the like, the sleeve 15 will simply be moved to a position to disengage the roller 14, whereupon the thrust block and the die blocks will be quickly removed from the carrier.

The advantages of the present invention arise from the provision of a wire straightener having adjustable dies positively operable to a predetermined position at any time during the operation of the machine. Further advantages of the invention arise from the provision of adjustable dies of such construction that they are prevented from turning out of alignment and which are so mounted that they may be removed at will for changing or repolishing.

I claim:

1. In a wire straightener, a rotating carrier through which the wire is passed in a longitudinal direction and having a guide therein, a tensioning die mounted for movement in said guide, and means for straightening the wire including means exteriorly of the carrier and partially embracing the same for adjusting the tensioning die for applying tension to the wire while the carrier is rotating.

2. In a wire straightener, a rotating carrier through which the wire is passed in a longitudinal direction, said carrier having a plurality of straightening dies and a tensioning die, a guide for the tensioning die, a sliding collar for adjusting the tensioning die, and means for shifting the collar for applying tension to the wire while the carrier is rotating.

3. A wire straightener having a rotary member with a plurality of straightening dies therein, there being an angular guide in the straightener between adjacent dies, a wire tensioning die in said guide, a sliding collar on the straightener, means on the collar and tensioning die for moving said die into tensioning relation to the wire, and

means for shifting the collar while the carrier is rotating.

4. A wire straightener having a rotary member with a plurality of straightening dies therein, there being an angular guide in the straightener between adjacent dies, a wire tensioning die in said guide, a roller on one of the members of said die, a sliding collar on the straightener having a cam groove in which the roller is seated, and means for shifting the collar for adjusting the tensioning die.

5. A wire straightener having a rotary member with a plurality of straightening dies therein, there being an angular through guide in said member, a wire tensioning die formed of a plurality of members in said guide, a collar on the rotary member for retaining the die members in said guide, there being a cam groove in the collar for receiving one end of one of the die members, and means for shifting the collar along the rotary member during the rotation thereof for varying the tension of the die on the wire.

6. A wire straightener comprising a rotatable die carrying body, a plurality of dies

carried thereby between which the wire to be straightened is passed, an intermediately located two-part die, one part of the said two-part die being movable toward its opposite part and to wire engaging position, and a manually operated slidable member mounted upon the rotatable die carrier.

7. A wire straightener comprising a rotatable shaft provided centrally with a longitudinal aperture for the passage therethrough of a wire to be straightened, a plurality of transverse apertures for straightening dies, one of said apertures being located midway between the other apertures for the reception of a two-part die, a two-part die one part thereof being movable to and from its other part, a slidable member mounted upon the exterior of the shaft and rotatable therewith, said member having an inclined portion for engagement with the movable member of the die, and manually actuated means for reciprocating the slide to effect an inward movement of the movable part of the die.

In testimony whereof I have hereunto set my hand.

JOHN C. MALONE.
